DESIGN FOR A HAND WASHBOARD

Seymour Rabinowitz, New York, N. Y.

Application July 30, 1947, Serial No. 140,614

Term of patent 7 years

(Cl. D49—1)

To all whom it may concern:

Be it known that I, Seymour Rabinowitz, a citizen of the United States of America and a resident of the city of New York, in the county of Kings and State of New York, have invented a new, original, and ornamental Design for Hand Washboard, of which the following is a specification, reference being had to the accompanying drawing, forming a part thereof.

Fig. 1 is a front view of a hand washboard showing my new design,

Fig. 2 is a rear view thereof, and

Fig. 3 is a top view thereof.

I claim:

The ornamental design for a hand washboard, substantially as shown.

SEYMOUR RABINOWITZ.
